US0D1098500S

(12) **United States Design Patent** (10) **Patent No.:** **US D1,098,500 S**
(45) **Date of Patent:** **** Oct. 14, 2025**

(54) **CONNECTOR FOR MOLDING**

(71) Applicant: **MCS Industries, Inc.**, Easton, PA (US)

(72) Inventors: **Matthew Scott Kressin**, Allentown, PA (US); **Robert Terry Coyle, Jr.**, Palmer, PA (US)

(73) Assignee: **MCS Industries, Inc.**, Easton, PA (US)

(**) Term: **15 Years**

(21) Appl. No.: **29/971,516**

(22) Filed: **Nov. 4, 2024**

Related U.S. Application Data

(62) Division of application No. 29/824,700, filed on Jan. 26, 2022, now Pat. No. Des. 1,054,595.

CLAIM

The ornamental design for a connector for molding, as shown and described.

DESCRIPTION

FIG. 1 is a front perspective view of a connector for molding showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines illustrating portions of the connector for molding form no part of the claimed design.

1 Claim, 6 Drawing Sheets
